UNITED STATES PATENT OFFICE.

ADAM H. PRENZEL, OF HALIFAX, PENNSYLVANIA.

METHOD OF MAKING SHOES.

Application filed March 9, 1920. Serial No. 364,382.

To all whom it may concern:

Be it known that I, ADAM H. PRENZEL, a citizen of the United States, and a resident of Halifax, in the county of Dauphin and 5 State of Pennsylvania, have invented certain new and useful Improvements in Methods of Making Shoes, of which the following is a specification.

My invention relates to improvements in 10 methods of making shoes, reference being had to my co-pending application for patent on shoes and method of making under-wedge shoes, filed Sept. 16, 1919, Serial No. 324,149, and it consists in the constructions and the 15 hereinafter enumerated steps of the method.

One of the foremost objects of the invention resides in the employment of the herein described improved method, by means of which a very substantial shoe is made, the 20 method being employed more particularly in manufacturing children's shoes.

A further object of the invention is to carry out the herein described method of which several of the important steps consist 25 in separately sewing an insole and outsole onto the upper leather and lining of the shoe, thus securing a doubly sure attachment of the shoe upper.

Other objects and advantages will appear 30 in the following specification, reference being had to the accompanying drawings, in which:—

Figure 1 is a plan view of an insole which is cut out in the shape shown in the first 35 step of the method,

Figure 2 is a perspective view illustrating the second step of the method, wherein the cut sole is placed in a mold,

Figure 3 is a longitudinal sectional view 40 showing how the insole is folded with an upstanding peripheral flange in carrying out the second step of the method,

Figure 4 is a detail perspective view of the sole after it comes from the mold,

Figure 5 is a perspective view illustrating 45 the third step of the method wherein the upper leather and lining of a shoe are temporarily affixed at desired places to the peripheral flange of the insole.

Figure 6 is a detail perspective view illustrating 50 the use of tacks as the affixtures instead of staples, as in Figure 5,

Figure 7 is a perspective view illustrating the fourth step of the method wherein the

upper leather and lining is primarily 55 stitched to the insole at the base of the peripheral flange,

Figure 8 is a perspective view illustrating the fifth step of the method wherein the temporary affixtures are removed, the flange 60 of the insole straightened out and a coating of cement is applied,

Figure 9 is a perspective view illustrating an outsole with an affixed spring heel wedge all coated with cement, which sole is applied 65 to the insole in Figure 8 in the sixth step of the method,

Figure 10 is a perspective view illustrating the seventh step of the method wherein a secondary row of stitching secures the out- 70 sole, insole, lining and upper leather of the shoe,

Figure 11 is a detail sectional view on the line 11—11 of Figure 10, illustrating the appearance and location of the two rows of 75 stitching,

Figure 12 is a detail sectional view illustrating a slight modification, specifically described below, and

Figure 13 is a detail perspective view 80 illustrating the use of a welt strip to conceal the exposed rows of stitching in Figure 10 and give the shoe a more finished appearance.

In order that the reader may obtain a 85 clear understanding of the method of making shoes as now proposed, but before describing the various steps, a brief introduction of one of the main purposes of the invention may be of advantage. The sole 90 1 is the foundation on which the whole shoe is built and on which the novelty of the process rests.

It is known in the art as a slip sole, that is to say, it is a sole of that kind usually 95 used in welt or McKay shoes to increase the weight of the sole. In such shoes there is an insole, slip sole and out sole, the insole naturally coming next to the foot. In such construction, the upper is fastened to the insole, leaving an edge on the inside which becomes very uncomfortable when the upper spreads from the insole by the wearing of the shoe.

According to the improved process, the 105 insole, as such, is entirely done away with. The slip sole is taken in the first instance, folded with a peripheral flange, thus turn-

ing it into the shape of an insole, then flattening the flange out, turning the sole back into the original slip sole but giving an extension edge which the ordinary insole 5 cannot give. Consider now the steps of the process.

Step No. 1

consists of cutting out an insole 1 according 10 to the particular size of shoe in the course of manufacture. The sole is cut out or stamped by any of the approved means now in common use. The dotted line 2 in Figure 1 approximately designates the place along 15 which an upstanding flange is formed according to step No. 2.

Step No. 2

consists of molding a peripheral flange 3 20 around the edge of the insole 1, as just stated above. This is done by placing the sole 1 on a mold block 4 with an opening 5 of the same shape as the sole 1 but small enough for the purpose of enabling the formation 25 of the flange 3 when the complementary molding plunger 6 is presented as in Figure 3.

In order to enable the molding of the flange 3 it is necessary to first soak the sole 30 1 in water so as to render it sufficiently soft that it may be operated on. The sole should remain in the mold sufficiently long that it may dry in the desired shape which is illustrated in Figure 4. To this end a great 35 number of molds are necessarily required, but these are cheaply provided because they merely consist of the sole-shaped plungers 6 and mold block 4 with complementary sole-shaped openings 5. The mold block 4 can 40 consist of a long piece with rows of openings 5, for each of which there will be a separate plunger 6.

Step No. 3

45 consists of temporarily affixing the upper leather 7 and canvas lining 8 of a shoe to the peripheral flange 3, by means of staples 9. These staples are pressed through near the edge of the flange and are placed wherever desired.

The illustration in Figure 5 shows the staples 9 as being introduced only at the tip of the shoe, the upper leather being drawn tightly around the flange in this 55 case, only requires the fixtures at the points indicated. A counter 10 is inserted at the heel between the upper leather 7 and lining 8. A wooden last is also inserted on the inside of the shoe to facilitate the carrying out of the method from this step on. The last is not indicated in the drawing but Figure 5 shows a number of tacks 11 by means of which the insole 1 is temporarily 60 secured to the last. It is desired to point out that instead of employing staples 9 as

the temporary affixing means between the flange 3 and shoe upper leather and lining, tacks 12 may be employed as in Figure 6. These are driven through and the points are clinched on the inside.

70

Step No. 4

consists of primarily stitching the upper leather and lining to the base of the flange 3 as at 13. This primary row of stitching 75 13 also goes through the counter 10 at the heel and permanently secures the parts together. It is here that the purpose and value of the peripheral flange 3 becomes apparent. The row of stitching 13 is made by a machine 80 employing an arcuate needle. This needle reciprocates in a curved path, entering holes from the outside of the shoe to the inside of the flange 3, previously made for the purpose by a perforating awl which is a 85 part of the machine. This machine also includes a guide finger which cooperates with the awl and needle in providing a support and advancing the shoe step by step so as to accommodate or cooperate with the stitching mechanism. This guide finger works on the inside of the flange 3 at the base of the sole 1, and moves around in the corner between the flange and pawl, which acts as a 90 guide therefor.

95

Were it not for the provision of the flange 3, this particular method of sewing could not be carried out, because it would be absolutely impossible to produce the stitching 13 by means of the curved needle described. Furthermore, it has been found by experience that the stitching operation, that is to say, the primary stitching operation, can not be carried out by a straight needle, because were this attempted, it would mean 100 that the stitching would have to be introduced without turning up the flange 3 and in such case, it could never be gotten in as closely as illustrated in Figure 11. In other words, the row of stitching 13 is inset, the adjacent upper part extending over the stitching and in a measure affording it protection. It is also to be observed that the inner row 13 does not come in contact with the ground.

105

110

115

Step No. 5

consists of removing the temporary affixing means 9, straightening out the flange 3, as illustrated in Figure 8, and applying a coating of cement, as indicated by the shading. When thus straightened out, the insole 1 is perfectly flat and so obviates the use of a filler as is customary and necessary in the manufacture of certain shoes in which in 120 the course of manufacture, a slight depression is left on the inside of the stitching.

125

It is to be observed in Figure 8 that the upper leather and lining of the shoe are turned with the flange 3. That is to say, 130

when the flange 3 is straightened out, the attached upper leather and lining are turned out as illustrated in the upper part of Figure 11.

5 *Step No. 6*

10 consists in applying the outsole 14 in Figure 9. This sole has a spring heel wedge 15 tacked thereto at 16, and a coating of cement is applied as indicated by the shading. The shoe is now ready for the performance of

15 *Step No. 7*

20 which consists of secondarily stitching the outsole 14, insole 1, lining 8 and upper leather 7 together. This secondary and final row of stitching 17 also goes through the wedge 15 and counter 10 at the heel. The resultant shoe in Figure 10 is very substantial, the double row of stitching adding greatly to the security of the out and insole. The outwardly turned parts of the shoe upper obviate the use of welting around the edge, that is to say, such welting is not 25 necessarily applied unless desired. But Figure 13 illustrates the application of welting 18 which is affixed by a third row of stitching 19.

30 The welt strip 18 is supplied as an article of manufacture and simply requires to be stitched on in case it be desired to conceal the two rows of stitching 13, 17. The row of stitching 19 is inserted by a curved needle, a straight needle being used to insert 35 the row of stitching 17 which is farther away from the body of the shoe.

The modification in Figure 12

40 adapts a part of the foregoing method of making children's shoes, to making shoes for adults. Here it is to be observed that the insole 1 is employed, the flange 3 being turned down as before. The primary row of stitching 13 secures the upper leather 7 and lining 8 to the flange.

45 But instead of extending the flange around the heel, that portion thereof is cut off as indicated at 20. Consequently, the back of the shoe is not capable of being 50 sewn in place and therefore tacks 21, or equivalent means, are employed to secure the in-turned portion generally designated 55 22, to the insole 1. A molded counter 23 is used in this shoe. This counter includes the molded flange 24 through which the tacks 21 pass as indicated.

A high heel 25 is suitably secured to the flat place on the insole 1 behind the cut-away portion 20. Types of heels other than 60 that illustrated in dotted lines in Figure 12, may be applied to the place provided on the insole by cutting away the heel portion of the flange 3. The remainder of the method beginning at Step No. 5 is to be 65 carried out in connection with the form in

Figure 12, that is to say, the flange 3 is turned out flat and an outsole is applied by means of the secondary row of stitching 17, as fully described above.

I claim:

1. The method of making shoes, consisting of cutting a sole, and moistening it to make it pliable; molding the sole to produce a peripheral upstanding flange and provide a guide, sewing a shoe upper leather 75 and lining close to the base of the flange, straightening out the flange to form a flat surface, and applying a coating of cement thereto; applying a cement-coated outsole, and running a second row of stitching 80 nearer the edge of the shoe sole, through both soles, the upper leather and lining.

2. The method of making shoes, comprising cutting a slip sole, and moistening it to render it pliable; molding said slip sole to produce an upstanding peripheral flange, temporarily affixing a shoe upper structure drawn over the flange, primarily stitching the upper structure to the flange close to the base, straightening the flange to 85 form a flat slip sole surface, and applying a cement coating thereto, said sewn upper structure being turned with the flange; applying a cement-coated outsole with an attached spring heel wedge, and applying a secondary outer row of stitches through both soles, wedge, lining and upper leather.

3. The method of making shoes, comprising cutting an insole, and moistening it to render it pliable; molding said sole to produce an upstanding peripheral flange, temporarily affixing a shoe upper leather and lining drawn over the flange, primarily stitching the upper leather and lining to the flange close to the base, straightening the flange to form a flat insole surface, and applying a cement coating thereto, said sewn upper leather and lining being turned with the flange; applying a cement-coated outsole with an attached spring heel wedge, 100 applying a secondary outer row of stitches through both soles, wedge, lining and upper leather, and covering both rows of stitches by a welt strip which is sewn in place.

4. The method of making shoes, including taking an insole having a peripheral upstanding flange, drawing a shoe upper leather and lining over the flange until it substantially meets the edge, temporarily securing the two, and running a primary row of stitching through the flange, lining and upper leather close to the base, and in the plane of the sole with a curved needle.

5. The method of making shoes, including molding a peripheral flange on an insole by turning the edge at right angles, drawing the upper leather and lining of a shoe over the flange until it substantially meets the edge, running a primary row of stitching around the base of the flange through the 125 130

lining and upper leather in the plane of the sole with a curved needle, said flange then serving as a guide for the associated guide finger of said needle; and turning the flange so as to provide a flat insole surface, which then has a row of stitches spaced in from the edge.

6. The method of making shoes, including taking an insole with a peripheral flange 10 turned at right angles thereto, drawing thereover a shoe upper leather, lining with a counter inserted between the lining and upper leather at the heel; running a primary row of stitching close to the base of 15 the flange, through the lining, counter and upper leather, with a curved needle which inserts the stitches in the plane of the sole, the flange acting as a guide for the associated guide finger of the needle; turning 20 the flange straight with the insole, at which time the corresponding portions of the upper leather, lining and counter are turned outwardly; suitably applying an outsole with an affixed spring heel wedge, and running a secondary row of stitching through 25 both soles, wedge, counter, lining and upper leather with a straight needle.

7. The method of making shoes, including taking an insole with a peripheral 30 flange turned at right angles thereto, drawing thereover a shoe upper leather, lining with a counter inserted between the lining and upper leather at the heel; running a primary row of stitching close to the base 35 of the flange, through the lining, counter and upper leather, with a curved needle

which inserts the stitches in the plane of the sole, the flange acting as a guide for the associated guide finger of the needle; turning the flange straight with the insole, at 40 which time the corresponding portions of the upper leather, lining and counter are turned outwardly; suitably applying an outsole with an affixed spring heel wedge, running a secondary row of stitching 45 through both soles, wedge, counter, lining and upper leather with a straight needle, and applying a welt strip with a third row of stitching, to conceal the two preceding rows.

8. The method of making shoes, consisting of taking an insole with an upstanding peripheral flange, drawing a shoe upper leather, lining and interposed counter over 50 said flange until they meet the edge, suitably temporarily affixing the upper leather and lining to said flange at desired places, running a row of stitching around the base of the flange through the lining, counter and upper leather, with a curved needle so that 55 the stitches are in the plane of the sole; turning the flange flat with the sole, at which time the upper leather, lining and counter are also turned, suitably applying an outsole with a secured spring heel wedge, 60 the primary row of stitches stopping at the joint between said soles; and running a secondary row of stitching through both soles, wedge, counter, lining and upper leather with a straight needle near the 65 periphery.

ADAM H. PRENZEL.
